NAME SIGN AND BRACKET FOR MAIL
BOXES AND THE LIKE

Harold W. Duncan, Akron, Ohio

Application January 25, 1949, Serial No. 72,635

9 Claims. (Cl. 40—145)

1

This invention relates to name signs for mail boxes, and for similar articles, and, more particularly, is concerned with signs of the indicated type utilizing insertable letters whereby any particular desired name can be spelled out.

Heretofore, it has been the usual practice in conjunction with rural type mail boxes to paint the name of the persons owning the mail box on the sides thereof. The result is a very amateurish lettering job unless a relatively expensive stencil is cut, and in any event, the paint will fade and dirty so that in several year's time it is necessary to repaint and reletter the mail box. This is a job which many mail box owners let slide with the result that it is often difficult to make out the name on a mail box and to locate the house of a given party.

Some efforts have been made heretofore to provide replaceable letter types of signs for one purpose and another, but so far as I am aware, none of these replaceable letter type signs are particularly adapted to rugged outdoor use, and specifically in association with a mail box. The known types of signs are either susceptible to deterioration by weather, fail to provide adequate thickness of metal or other section to make the sign substantial and attractive, or go to the other extreme of casting metal letters which becomes a relatively expensive proposition.

It is the general object of my invention to avoid and overcome the foregoing and other difficulties of and objections to prior art practices by the provision of an improved name sign and bracket assembly adapted to receive selected letters, with the assembly being attractive, durable, and relatively inexpensive, as compared to known removable letter type signs.

Another object of my invention is to provide a bracket for use in conjunction with a mail box of the rural type, the bracket being adapted to receive and support selected letters identifying the owner of the mail box.

Another object of my invention is the provision of an assembly of the type described in which stamped aluminum letters of considerable strength and thickness are removably received in an extruded aluminum section having an inverted T-slot formed longitudinally thereof.

Another object of my invention is to provide a name and mail box combination including red reflector buttons for warning an automobile away from the side of the road and the vicinity of the mail box to add a safety feature to the road and to protect the mail box of the combination.

2

Another object of my invention is to provide a combination mail box support bracket and selective letter receiving means.

The foregoing objects of my invention and other objects which will become apparent as the description proceeds are achieved by the provision of the combination including a mail box, an extruded aluminum section having an inverted substantially T-shaped slot therein, a plurality of letters having footer portions slidably received in the slot, the footer portions having a plurality of oppositely directed legs bent out of the plane of the letter, the footer portions preferably being longer in the direction of length of the slots than the width of each letter to effect spacing between the letters, the footer portions being pushed together end to end in the slot, means for securing the letters in the slot, and means for connecting the mail box and section in spaced parallel relation. The section may be curved at one end of the letters and a reflector button may be carried in the curved portion of the section. In one form of the invention the section and letters are mounted on top of the mail box, and in another embodiment of the invention the section is curved to provide a bracket which not only receives and supports the letters but also which serves to support and carry the mail box.

For a better understanding of my invention, reference should be had to the accompanying drawing, wherein:

Fig. 1 is a side elevation of a mail box and name sign combination incorporating the principles of the invention;

Fig. 2 is an enlarged transverse cross-sectional view taken substantially on line 2—2 of Fig. 1;

Fig. 3 is an end elevation of a typical letter incorporated in the invention, and with the supporting channel of Fig. 2 being shown in chain dotted lines;

Fig. 4 is a front elevation of the typical letter illustrated in Fig. 3 of the drawings;

Fig. 5 is a side elevation similar to Fig. 1, but illustrating a second embodiment of my invention; and

Fig. 6 is an enlarged fragmentary view taken substantially on line 6—6 of Fig. 5.

It should be understood that the principles of my invention, and particularly the removable letter name sign portions thereof, are adaptable to a wide variety of uses and purposes. However, the invention is most particularly and beneficially employed in combination with a rural type mail box, and, has accordingly been so illustrated and will be so described.

In the drawings, the numeral 10 indicates a vertically extending post which supports from underneath a rural type mail box 12 of standard shape and construction in known manner. Associated with the mail box 12 and positioned above and parallel to the top of the mail box is a metal section or channel indicated as a whole by the numeral 14. The metal channel 14 is conveniently formed in an extruded aluminum section of the shape shown in Fig. 2, with a flat base 16 and two upstanding ribs or flanges 18 which define an inverted T-shaped channel 20.

The upstanding flanges 18 are milled, or otherwise removed from the section 14 adjacent the opposite ends thereof, with one of the ends 22 being directed downwardly at substantially a right angle, and being adapted to be secured by bolts or rivets 24 to the back of the mail box 12. The other end of the metal section 14, at 26, is rolled into an eye which receives and supports a round red light reflecting button 28 which serves to protect the mail box and act as a safety guide for persons or vehicles passing near the box. A spacer clamp or bracket 30 secured between the mail box 12 and the metal channel 14 near its front end additionally serves to support and strengthen the section 14.

Adapted to be selectively positioned in the T-shaped channel 20 of the metal section 14 are a plurality of letters, numbers, punctuation marks, or the like, these being indicated as a whole by the numeral 32, and being stamped from relatively thick metal, preferably aluminum, at least $\frac{1}{8}$ of an inch thick, and preferably approaching $\frac{1}{6}$ of an inch whereby the letters will have a third dimensional thickness which materially adds to their appearance and strength.

A footer is formed in association with the bottom of each one of the letters 32 and this is preferably accomplished by bending alternate legs 34 out to substantially right angles from the plane of the letters, the leg or footer portions 34 being adapted to be slidably received in the channel of the metal section 14. It will be noted that the footer or leg portions 34 are preferably made of a greater length in the direction of the channel 20 than the width of the letters 32 to thereby provide spacing between the letters.

One end of the channel 20 is at least partially closed by suitable means which can be conveniently accomplished by bending one or both of the flanges 18. The letters are introduced into the channel 20 from the opposite end of the channel and are moved up against the means closing the one end of the channel, the footer portions 34 striking each other end to end. When all of the letters have been introduced, the other end of the channel 20 is closed adjacent the last letter in the channel, again by bending the flanges 18 with a pair of pliers or by distorting the channels with a center punch or the like to thereby lock the letters in position in the channel.

In the embodiment of my invention illustrated in Figs. 5 and 6, and upstanding wooden or metal post 40, or it might be a tree or a side of a building, or the like, is adapted to receive and support a bracket portion indicated as a whole by the numeral 42. The bracket 42 comprises a metal section, usually provided by extruded aluminum to the cross-sectional shape shown in Fig. 6 of the drawing, with the metal section being bent near its center to provide a loop 44, and being bent at its ends to provide vertically aligned legs 46 and 48. The legs 46 and 48 are secured to the posts 40 by screw or like means 50. Artistic

metal straps 52 may be secured between the leg 46 and the upper portion of the bracket 42 for strengthening and decorative purposes.

It will be recognized from Fig. 6 that the metal section of the bracket 42 is formed with a substantially flat base portion 54, a central rib 56, and an inverted T-shaped slot 58. The slot 58 is on the inside of the bracket 42 so that with the bracket shaped in the manner shown, a round red reflector button 60 may be received in the loop 44 of the bracket, with the button resting in the slot 58, and being peened into position by means of a center punch or the like, which will deflect or distort the metal surrounding the T-slot 58 at the edges of the disc 60 to lock it in position.

Removably received in the slot 58 in the bottom portion 62 of the bracket 42 are a plurality of letters 64 having oppositely extending footer or leg portions 66 bent out of the plane of the letter which will slide snugly in the slot 58. The letters 64 can be inserted in the lower portion 62 of the bracket 42 prior to the time that the leg 48 is bent, or a slot 68 can be milled into the metal section in the region of the bend of the leg 48 to facilitate the introduction of the letters after the leg 48 is bent but before the bracket 42 is applied to the post 40.

A pair of cast metal clamps 70 are slipped over the metal channel section 62, and appropriate hooks 72 are secured to the top of a mail box 74, with each hook 72 being extended through an eye provided in the bottom of the clamps 70.

In both forms of the invention illustrated and described a very neat, sturdy, durable and long wearing mail box and name combination are provided. It is a relatively simple matter at the store to buy the metal section and the proper letters to spell out the customer's name, with the letters being quickly inserted into the metal section and secured in position. The aluminum construction of the assembly is particularly resistant to weathering, and possesses very considerable beauty over the years without the necessity to paint it. However, even if it is desirable to paint the assembly, this can be done without destroying the silhouetted name. The form of the invention shown in Fig. 5 not only functions to support the mail box, but also provides protection for the letters 64, the letters being positioned between the upper and lower portions of the bracket.

While in accordance with the patent statutes, I have specifically illustrated and described at least one best known embodiment of my invention, it is to be particularly understood that I am not to be limited thereto or thereby, but that the scope of my invention is defined in the appended claims.

I claim:

1. An insertable letter sign comprising an extruded aluminum section having an inverted T-slot lengthwise thereof, one end of the section being cut away to remove the slot and leave a flat bar portion, the flat bar portion being bent downwardly and adapted to be secured to a mail box or the like, means at least partially closing the slot adjacent one end thereof, a plurality of letters, a footer on each letter of greater length than the width of the letter, said footer being formed by a plurality of integral legs bent in opposite directions out of the plane of the letter, said footers being slidably received in the slot in end to end contact and being pushed against

the closing means, and means closing the other end of the slot to secure the letters in position.

2. An insertable letter sign comprising an extruded aluminum section having an inverted T-slot lengthwise thereof, means at least partially closing the slot adjacent one end thereof, a plurality of letters, a footer on each letter of greater length than the width of the letter and of a height to position the bottom edge of the letter in approximate alignment with the top edge of the T-slot, said footer being formed by a plurality of integral legs bent at substantially right angles in opposite directions out of the plane of the letter, said footers being slidably received in the slot in end to end contact and being pushed against the closing means, and means closing the other end of the slot to secure the letters in position.

3. In combination, a mailbox, an extruded aluminum section having an inverted T-slot lengthwise thereof, one end of the section being cut away to remove the slot and leave a flat bar portion, the flat bar portion being bent downwardly and secured to the back end of the mail box, means at least partially closing the slot adjacent one end thereof, a plurality of letters, a footer on each letter of greater length than the width of the letter, said footer being formed by a plurality of integral legs bent in opposite directions out of the plane of the letter, said footers being slidably received in the slot in end to end contact and being pushed against the closing means, and means closing the other end of the slot to secure the letters in position.

4. A name sign and mail box bracket including an extruded aluminum section having a longitudinally extending T-slot therein, said section being bent near its center with the slot on the inside to form two portions in spaced parallel relation to each other, the upper portion being bent upwardly and the lower portion being bent downwardly to form vertically aligned feet for securing the bracket to the side of a post or the like, artistic strengthening means extending between the upper foot and the upper portion, a plurality of letters having footer portions of greater length than the widths of the letters being received in the slot of the lower portion and extending upwardly between the lower and upper portions, bracket means for securing a mail box to the lower portion, and a reflector button carried in the slot of the section near the region of its center bend.

5. A name sign and mail box bracket including an extruded aluminum section having a longitudinally extending T-slot therein, said section being bent near its center with the slot on the inside to form two portions in spaced parallel relation to each other, the upper portion being bent upwardly and the lower portion being bent downwardly to form vertically aligned feet for securing the bracket to the side of a post or the like, artistic strengthening means extending between the upper foot and the upper portion, a plurality of letters having footer portions received in the slot of the lower portion and extending upwardly between the lower and upper portions, and bracket means for securing a mail box to the lower portion.

6. In combination, a mail box, a support for the mail box, a metal section having a longitudinally extending T-slot therein, said section being bent near its center with the slot on the in-

side to form two portions in spaced parallel relation to each other, the upper portion being bent upwardly and the lower portion being bent downwardly to form vertically aligned feet for securing the bracket thus formed to the side of the post, artistic strengthening means extending between the upper foot and the upper portion, a plurality of letters having footer portions received in the slot of the lower portion and extending upwardly between the lower and upper portions, and bracket means supported on the lower portion and secured to the top of the mail box.

7. In combination, a mail box, an extruded aluminum section having an inverted T-slot lengthwise thereof, one end of the section being cut away to remove the slot and leave a flat bar portion, the flat bar portion being bent downwardly and secured to the back end of the mail box, a spacer bracket securing the other end of the section to the mail box so as to support the section in spaced parallel relation along the top of the mail box, means at least partially closing the slot adjacent one end thereof, a plurality of letters, a footer on each letter of greater length than the width of the letter, said footer being formed by a plurality of integral legs bent in opposite directions out of the plane of the letter, said footers being slidably received in the slot in end-to-end contact and being pushed against the closing means, and means closing the other end of the slot to secure the letters in position.

8. An insertable letter sign comprising an extruded aluminum bar section having a flat base and integral opposed upwardly and inwardly directed flanges defining an inverted T-slot extending lengthwise thereof, a plurality of aluminum letters having a thickness substantially equal to the thickness of the base of the bar section, a footer on each letter received in the T-slot, each footer including a plurality of legs integral with the letter and bent in opposite directions on a gradual curve to a right angle position wherein the ends of the legs engage slidably with the flat base and the flanges of the bar section, the upper edges of the flanges slidably engaging the footer immediately below the letter and above the legs, and means securing the footers in the bar section.

9. An insertable letter sign comprising a bar section having a flat base and opposed upwardly and inwardly directed flanges defining, together with the base, an inverted T-slot extending lengthwise thereof, a plurality of letters having a thickness of at least about one-eighth of an inch, a footer integral with each letter and received in the T-slot, and a plurality of legs integral with the footer and of substantially the thickness of the letter extending at substantially a right angle out from the sides of the footer and slidably received in the cross bar portion of the T-slot.

HAROLD W. DUNCAN.
